UNITED STATES PATENT OFFICE.

LEE S. CHADWICK, OF EAST CLEVELAND, OHIO, ASSIGNOR TO THE CLEVELAND FOUNDRY COMPANY, OF CLEVELAND, OHIO, A CORPORATION OF OHIO.

LIFTING DEVICE FOR COMBUSTION-TUBES.

1,212,902.

Specification of Letters Patent. Patented Jan. 16, 1917.

Application filed September 7, 1915. Serial No. 49,405.

To all whom it may concern:

Be it known that I, LEE S. CHADWICK, a citizen of the United States, residing at East Cleveland, in the county of Cuyahoga and 5 State of Ohio, have invented a certain new and useful Improvement in Lifting Devices for Combustion-Tubes, of which the following is a full, clear, and exact description, reference being had to the accompanying 10 drawings.

This invention relates generally to oil or vapor burners and more particularly to the means for raising and lowering the combustion or commingling tubes employed in connection with the wick or burner proper.

One object of the invention is to provide a simple and efficient means whereby the combustion or commingling tubes can be quickly and easily raised and supported away from 20 the wick, so that the burner can be lighted.

Another object of the invention is to provide means for properly positioning the combustion tubes upon the wick tube after the burner has been lighted.

25 A still further object of the invention is to provide a simple and efficient means for raising and lowering the combustion or commingling tubes which can be used in connection with any type of wick stop without interfering in the least with said stop.

With these and certain objects in view, the invention consists in the novel features of construction and combination herein after fully described and pointed out in the claims.

35 In the drawings forming a part of this specification, Figure 1 is a central vertical section through an oil burner provided with my improved means for raising and lowering the combustion or commingling tubes,

40 said tubes being shown in their lowered or normal position; Fig. 2 is a similar view showing the tubes raised to permit the lighting of the wick; and Fig. 3 is a detail perspective view illustrating the locking means.

45 In carrying out my invention I provide a wick holder 10 comprising the inner and outer wick tubes which are united at their lower ends as usual, and near their upper ends are constructed with the inner and 50 outer annular ledges 11 and 12, respectively, upon which rest the inner and outer combustion or commingling tubes 13, and 14 respectively, said combustion tubes being positioned and supported in a drum 15 by any 55 suitable means such as cross-rods 16. This

drum is preferably provided with the handle 17, constructed as shown, or another form of handle may be employed if desired.

At the lower end of the inner commingling tube 13, is a perforated diaphragm 18, carrying a central thimble 19 which is bored centrally to receive the upper end of the lifter rod 20, said rod extending downwardly through the ring-like wick stop 21, and through an elongated slot 22, produced 60

in a strap 23 arranged within the inner wick tube near the lower end thereof, one end of said strap being secured to the inner wick tube as shown, while the other end of 65 said strap is projected downwardly below the lower end of wick tube as shown at 24.

This downwardly projecting end may be somewhat broader than the strap, and is longitudinally slotted from the end of wick tube downwardly as shown at 25, the upper 70

end of the slot having the lateral notches 26, which are adapted to receive the ribs or fins 27, swaged upon the outwardly projecting portion 28 of the lifter rod 20, said rod, after 75

passing through the slot 22 being bent at 29 to accommodate the oil pipe, (not shown) and is then bent at 30 so as to project the free 80

end thereof through the slot 25, the extreme end of the lifter rod being curved as indicated to provide a suitable handle. By 85

means of this rod constructed as herein shown and described and connected to the commingling or combustion tubes by the central thimble and perforated diaphragm, I am able to raise and lower the commingling 90

or combustion tubes at will, by simply raising and lowering the lifting rod, and it will be noted that when the rod is grasped at its lower end, and lifted for the purpose of raising the commingling or combustion tubes 95 clear of the burner, the said tubes will tilt slightly to one side as shown, inasmuch as the lifting rod is permitted to rock rearwardly on account of the slot 22 in the strap 23, and this tilting motion of the commingling tubes provides a greater space at the front where the lighting is to be done.

100 It will be noted that the ribs or fins 27 bear against the inner face of the depending portion 24 when the rod is in its lowermost position, and also until it reaches its uppermost position, at which time the tilting strain upon the rod serves to project the swaged portion through the lateral slots 26 and thereby hold the lifting rod in its raised 110

or uppermost position, maintaining the commingling or combustion tubes elevated until the lighting operation has been accomplished. Then by pushing the handle inwardly to disengage the fins or ribs, the rod 20 can be lowered and these fins or ribs engaging the rear face of the depending portion 24 insures the commingling or combustion tubes to be properly seated upon the 10 supporting ledges of the wick tubes.

It will be understood that the wick stop can be of any desired construction and it can be omitted entirely as the tube raising means here shown is entirely independent of any 15 wick stop construction.

It will thus be seen that I provide a cheap, simple and efficient means for raising, lowering and positioning the combustion tubes with reference to the burner.

20 Having thus described my invention, what I claim is:—

1. The combination with a burner and combustion tubes, of a lifting rod connected at its upper end with said tubes, said rod 25 having a vertical and lateral tilting movement, and means attached to said burner for supporting said rod in its raised and shifted position.

2. The combination with a burner and 30 combustion tubes, of a lifting rod connected at its upper end with said tubes, a guide for said rod within said burner, said guide being slotted to permit a limited lateral movement of said rod and means attached to said 35 burner for supporting said rod in its raised and shifted position.

3. The combination with a burner and combustion tubes, of a lifting rod connected at its upper end with said tubes, said rod 40 having a vertical and lateral tilting movement, the lower end of said rod being projected outwardly beyond the burner, and means attached to said burner for guiding the vertical and outwardly projected portions of said rod.

4. The combination with a burner and combustion tubes, of a lifting rod connected at its upper end with said tubes, the lower 50 end being projected outwardly below the bottom of the burner and means attached to said burner for guiding the vertical and the outwardly projected portion of said lifting rod, said rod having a vertical and laterally tilting movement, the outwardly projecting 55 portion of said rod and that portion of the guiding means coöperating therewith being shaped to hold said rod in its elevated and tilted position.

5. The combination with a burner and 60 combustion tubes, of a perforated diaphragm

attached to the inner combustion tube, a thimble carried by said diaphragm, and a lifting rod extending upwardly through the burner and having its upper end fitted in said thimble, a slotted guide carried by said burner whereby said rod has a vertical and lateral movement and means carried by the burner for locking the lower end of said lifting rod in its raised and shifted position. 65

6. The combination with a burner and 70 combustion tubes, of a rod having its upper end connected with said tubes, the lower end of said rod being projected outwardly beyond the burner, and a guide attached to said burner and adapted to guide the vertical and outwardly projected portions of 75 said rod, the outwardly projected portion of said rod being provided with means for engaging a portion of said guide whereby the rod is caused to travel vertically until it reaches the limit of its elevation.

7. The combination with a burner and 80 combustion tubes, of a guide attached to said burner and comprising a horizontal and a vertical portion, said portions being slotted, 85 the upper portion of the vertical slot being enlarged, and a lifting rod comprising a vertical and a horizontal portion, the upper end of the vertical portion being connected with the combustion tubes, the horizontal 90 portion having enlargements adapted to engage the vertical guiding portion as set forth.

8. The combination with a burner and 95 combustion tubes, of a rod comprising a vertical and a horizontal portion, the upper end of the vertical portion being connected with the combustion tubes, a guide attached to the burner, said guide comprising a horizontal portion and a depending vertical portion, the horizontal portion having a centrally elongated slot, the vertical depending portion being slotted longitudinally, the upper portion of said slot being enlarged, the horizontal portion of said lifting rod 100 being enlarged and adapted to engage the depending slotted portion of the guide as set forth.

9. The combination, with a burner and 110 lifting member, of a lifting rod connecting at its upper end with said lifting member, said rod having a vertical and lateral movement and means operatively controlled by said lateral movement of said lifting rod for holding said lifting member in the 115 raised position.

In testimony whereof, I hereunto affix my signature.

LEE S. CHADWICK.
